CLAIM

The ornamental design for a beach tent, as shown and described.

DESCRIPTION

FIG. 1 is a front, top, and right perspective view of a beach tent showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a rear, bottom, and left perspective view thereof;
FIG. 9 is an enlarged detail view of area 9 circumscribed within FIG. 7.
FIG. 10 is an enlarged detail view of area 10 circumscribed within FIG. 1; and,
FIG. 11 is an enlarged detail view of area 11 circumscribed within FIG. 1.

The broken lines shown in the drawings represent portions of the beach tent that form no part of the claimed design.
